UNITED STATES PATENT OFFICE.

OTTO A. SEYFERTH, OF FAIRMONT, WEST VIRGINIA.

CONVEYER APPARATUS.

Application filed April 12, 1923. Serial No. 631,723.

To all whom it may concern:

Be it known that I, OTTO A. SEYFERTH, a citizen of the United States, residing at Fairmont, in the county of Marion and State of West Virginia, have invented certain new and useful Improvements in Conveyer Apparatus, of which the following is a specification.

This invention relates to conveying machinery and especially to that type of conveying machinery wherein an endless chain or rope provided at intervals with flights is used to drag or retard material along a trough.

More particularly the invention relates to a driving wheel or sprocket for conveyers of this description.

In the conveying of such heavy and coarse lump materials as coal and certain ores, it is common to erect a trough between the two points from which it is desired to convey or retard the material. At each end of this trough there is provided a wheel, and around these wheels is led an endless wire rope having what are commonly termed "buttons," clamped thereon at intervals intended to be regularly spaced.

One of the wheels in such a device constitutes the driving wheel which is commonly termed the bull wheel, and receives its power from suitable driving mechanism such as an engine, motor or the like. In such an arrangement, the bull wheel is formed with pockets to receive the buttons and thus constitutes, in principle, a sprocket wheel, the wire rope and buttons constituting the sprocket chain.

Under the conditions obtaining with this construction of conveyer, it is evident that there will not only be difficulty in evenly spacing the buttons on the rope, but there will be difficulty in maintaining the positions of the buttons because of the heavy stresses incident to moving the coal or ore along the conveyer. Consequently variations in position of the buttons will take place regardless of the care with which they may be originally positioned on the rope. Since the space between two adjacent buttons is equivalent to the pitch of a sprocket chain, it is evident that variations in this spacing, no matter how they occur, are equivalent to variations in pitch of the chain surrounding the bull wheel and because of this a bull wheel with a fixed or invariable pitch is ineffective at certain times or in

certain relative positions of the wheel and rope.

One important object of the present invention is to provide a novel form of bull wheel which will automatically adjust itself to variations in the spacing or pitch of the buttons.

Again, a conveyer system of this type, while the best under certain conditions which can be employed, is subject to sudden and violent changes in the stresses on the parts, such changes being brought about by corresponding variations in the resistance exerted by the load, and by climatic conditions. Consequently, with a bull wheel having a fixed pitch and driven uniformly, sudden increases in the tensile stresses exerted on the rope take place which not only stress the rope unduly, but tend to cause slipping of the buttons along the rope.

A second important object of the invention is to provide an improved and novel construction of bull wheel wherein these sudden excessive stresses and shocks will be prevented, or so lessened as to eliminate abnormal strains in or breakage of the parts of the device, and to decrease or eliminate slipping of the buttons on the rope.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Fig. 1 is a side elevation of a driving or bull wheel constructed in accordance with this invention.

Fig. 2 is an edge or face view of such a wheel, the view being taken from the left hand side of Fig. 1.

Fig. 3 is a diametrical section through the wheel on the line 3—3 of Fig. 1.

Fig. 4 is a section on the line 4—4 of Fig. 2.

Fig. 5 is an outline diagram of a conveyer system in which the invention may be used.

In the embodiment of the invention herein illustrated, the wheel consists of two symmetrical side members each of which comprises a hub 10 from which radiate flat plate spokes 11 well reinforced by ribs 12. On the outer ends of the spokes are the rims 13

provided with suitable gear teeth 14 so that they may be driven by two driving pinions P on the counter shaft of a suitable engine or motor E furnishing the motive power for the mechanism. Centrally of the outer end of each spoke, there is provided an outwardly bulged portion 15 forming one half of a pocket 16 for the reception of the buttons B on the rope R. On the inner face 10 of each spoke, there is provided a rectangular boss 17, and these bosses are of such height that their end faces bear against each other to hold the two sides of the wheel in properly spaced relation when assembled, 15 the sides being held together by bolts 18 and nuts 19. Thus the spokes 11 are spaced and are substantially parallel. Adjacent the hub, pivot bolts 20 extend between the spokes 11, and on these pivot bolts are 20 swingingly mounted the driving segments which engage the buttons B to drive the rope R. Each of these segments comprises a hub portion 21 which is pivoted on the respective bolt 20, and from which radiates 25 a pair of arms or spokes 22 carrying a rim segment 23 provided with a rope receiving groove 24. On the outer edge of each rim segment is a spring seat 25 located opposite a respective pair of the lugs 17, which are 30 similarly provided on the sides confronting the spring seats 25 with spring seats 26, coiled compression springs 27 which serve to hold the segments centrally between the lugs 17 in such manner that the segments 35 may yield to a certain extent when pulling stress is exerted on the rope R. Adjacent each end of each segment, stub shafts 28 are mounted in the spokes 11, these stub shafts being provided with heads 29 on their inner 40 ends to hold wheels 30 which engage the ends of the buttons B as they rest in the pockets 16, and thus constitute rotatable button stops.

With this construction the rope engaging 45 segments take the first stresses on the rope, and allow the buttons to come gradually against the guide wheels 30, thus avoiding sudden shocks and undue stresses on the working parts. Moreover, any variation in 50 the spacing or pitch of the buttons will be accommodated by the shifting of the segments in one direction or the other against the action of the springs 27.

It will be observed that the segments have 55 a less radius than the radius of the wheel itself so that no abrupt bends are made in the cable at the points where the cable engages with and disengages from the segment.

There has thus been provided a simple 60 and efficient device of the kind described and for the purpose specified.

It is obvious that minor changes may be 65 made in the form and construction of the invention without departing from the material spirit thereof. It is not, therefore,

desired to confine the invention to the exact form herein shown and described, but it is desired to include all such as properly come within the scope claimed.

Having thus described the invention, what 70 is claimed as new, is:

1. In a driving wheel of the class described, a wheel body comprising a plurality of wheels and rope engaging elements yieldably and pivotally mounted between said 75 wheels in peripherally spaced relation on said wheel body.

2. In a sprocket wheel for button provided conveyer ropes, a wheel body comprising separable wheels each being provided with spaced and alined peripheral button receiving cavities, the alined cavities forming peripheral pockets and yieldably mounted rope engaging elements between 80 said pockets.

3. In a sprocket wheel for button provided conveyer ropes, a wheel body provided with spaced peripheral button receiving pockets, rope engaging segments pivoted to 85 said body between said pockets for swinging movement between the pockets, and spring means normally holding the segments centrally between said pockets.

4. In a sprocket wheel for button provided conveyer ropes, a wheel body comprising spaced sides and having spaced peripheral button receiving pockets, and yieldably supported rope engaging elements pivoted between said spaced sides and alternating with said pockets.

5. In a sprocket wheel for button provided conveyer ropes, a wheel body comprising spaced sides and having spaced peripheral button receiving pockets, rope engaging segments pivoted between said sides and arranged alternately with said pockets, and spring means for holding said segments normally central between the pockets.

6. In a sprocket wheel for button provided conveyer ropes, a wheel body provided with spaced peripheral button receiving pockets, rope engaging segments pivoted to 110 said body between said pockets for swinging movement between the pockets, spring means normally holding the segments centrally between said pockets, and rotatable button stops at opposite ends of each pocket.

7. In a sprocket wheel for button provided conveyer ropes, a wheel body comprising spaced sides and having spaced peripheral button receiving pockets, rope engaging segments pivoted between said sides and arranged alternately with said pockets, spring means for holding said segments normally central between the pockets, and rotatable button stops at opposite ends of each pocket.

In testimony whereof, I hereunto affix my signature.

O. A. SEYFERTH.
